UNITED STATES PATENT OFFICE.

WILLIAM NICHOLAS, OF SOUTHPORT, CONNECTICUT, ASSIGNOR TO PREMIER MACHINE COMPANY, A CORPORATION OF DELAWARE.

FONT OF TYPE.

1,237,684.

specification of Letters Patent. Patented Aug. 21, 1917.

Application filed July 7, 1914. Serial No. 849,524.

To all whom it may concern:

Be it known that I, WILLIAM NICHOLAS, a subject of the King of Great Britain, residing at the town of Southport, county of 5 Fairfield and State of Connecticut, have invented certain new and useful Improvements in Fonts of Type, fully described and represented in the following specification and the accompanying drawings, forming a part of 10 the same.

My invention relates to printers' type and has for an object to provide fonts of type wherein the kerned portions will overhang and be supported by the body portion of the 15 contiguous type.

More specifically stated my invention relates to an improved form of construction of type kerns, and is especially adaptable to characters formed on type casting and composing machines. In the usual foundry made types of this class the kerns are supported by means of an enlargement of the body of the type below the character portion which necessitates a second handling in their 20 manufacture to complete the process of production thereof. This is obviously impossible in casting and immediately composing the type into lines of composition under the conditions of the operation of such machines. 25 To overcome the obstacles to the use of such kerned type in machine composition a font of type has been designed which forms the subject matter of the U. S. Patent No. 696,784 to G. A. Goodson, its kern 30 portions having as their support under cut right angle extensions which although not extending so far down the body portion of the type as in the construction of the so-called founders' type, it nevertheless requires the body of the type immediately adjacent thereto to be cut away correspondingly to an appreciable extent to allow clearance for the kern supporting bracket.

While the Goodson form of kern construction permits of the font to which it pertains being cast and composed upon a type-setting machine, it presents practical difficulties which it is one of the purposes of my invention to eliminate. That is to say, in the 45 Goodson type, for example, the kern and its supporting portions of the type body are cast within the constantly shifting matrix plate, while the remainder of the body portion of the type is formed by the corresponding 50 walls of the type mold. The two mold

members being thus held in operable positions by different means, the mold walls being rigidly attached to the frame of the machine, it will be apparent that no matter how carefully the matrix may be entered 60 over the type mold, in the process of composition, objectionable breaks will necessarily occur in lineaments of the character upon which the kern is cast, when the portion of the type body underlying the kern is 65 thus molded with the kern in the matrix, the remainder of the body being cast in the mold which is firmly and rigidly anchored to the frame of the machine. This variation in the surface of the type body, it is obvious, 70 may be aggravated by reason of the corresponding recess of the adjacent type, which is also cast in the movable matrix block and may therefore fail in being registered upon the body in the same manner, and which, as 75 often occurs, may be offset oppositely to a like irregularity in such contiguous adjacent type.

A further object of my invention is to provide a kerned type which does not require 80 other type to be especially formed to cooperate therewith, in designing the depth of the kern to that of the character only, the body portion being of a form to rest upon the shoulder of the adjoining type when cast 85 in the usual manner, which is especially applicable to the casting of script characters upon casting machines.

Having reference to the drawings: Figure 1 is a plan view of a portion of a line of type 90 having script faces; Fig. 2 is a view of the same type in front elevation; Fig. 3 is a view similar to Fig. 2, showing one type separated from another, and Fig. 4 is a plan of single type, having a form of my improved kern.

Having reference to the drawings, 1 represents an ordinary founder's type having the usual body portion 2 upon the top of which is the raised character portion 3. 100

In casting certain characters the raised portion 3 is extended laterally beyond the limits of the supporting body 2 thereby forming a kern 5 which is usually supported by an enlargement and reinforcement of the 105 underlying portion of the type. To allow for this built out portion, sufficient metal is removed from the abutting surface of the type bodies which in the process of composing the types into lines are contiguous to 110

such extended portion of the kerned type. In my present invention, however, I discard all under support of the kern of the type, constructing such over hanging position as a specially formed kern 5 having a plane under surface 6 parallel to that of the face of the character, at the even height of the shoulder 4 of the type.

The shoulders 4 of all the type of my improved font have been constructed, as is usual in type design, to form a lever surface likewise parallel to the face of the type and consequently the under surfaces 6 of the kerns will rest evenly upon the shoulder of the adjacent type which will constitute a perfect support therefor when the pressure incident to printing is placed upon the forms containing type of my improved form of kerns.

Furthermore either italic, script or Roman characters having kerns formed in accordance with the requirements of my improved font can be set on type casting machines wherein the characters are immediately

transferred to the galley in the form of composed lines. In such case no modification of the molds is required for the reason that the kerned characters are cast in the matrix plate entirely, which can be carried laterally into the galley upon the plate being raised therefrom.

Having described my invention, what I claim is:

A font of type having horizontally disposed shoulders at the top of the body portion thereof; kerns having an under surface horizontally disposed at the depth of the character portion adapted to rest upon the shoulder of the contiguous type as a seating surface for said kern when the type are formed into lines of composition.

In testimony whereof, I have hereunto set my hand in the presence of two subscribing witnesses.

WILLIAM NICHOLAS.
